UNITED STATES PATENT OFFICE.

MATTHEW MARSHALL, SR., OF VANCOUVER, BRITISH COLUMBIA, CANADA.

COOKING-OVEN.

1,227,060.

Specification of Letters Patent. Patented May 22, 1917.

Application filed December 13, 1916. Serial No. 136,612.

To all whom it may concern:

Be it known that I, MATTHEW MARSHALL, Sr., a citizen of the Dominion of Canada, residing at Vancouver, in the Province of 5 British Columbia, Canada, have invented certain new and useful Improvements in Coking-Ovens, of which the following is a specification.

This invention relates to an improvement 10 in a coal coking oven, the improvements being particularly directed to a means for recovering all available by-products from the volatile matter of the coal, without reducing the quantity or impairing the quality of the 15 coke produced.

This object is attained by providing the floor of the oven with uniformly distributed apertures through which the volatile matter given off from the coal by the heat may be 20 drawn for delivery to the condensers, etc., and by a provision by which any dust or solid matter that may pass through the floor apertures is trapped in channels, access to 25 which is obtained for purposes of removal through closable apertures in the front of the oven.

The invention is particularly described in the following specification, reference being made to the drawings by which it is accompanied, in which:

Figure 1 is a vertical section on the line 1—1 in Fig. 2.

Fig. 2 is a plan on the line 2—2 in Fig. 1 with parts of the floor bricks removed.

Fig. 3 is a vertical section on the line 3—3 in Fig. 2, and

Fig. 4 is a cross section and perspective view of the floor of the coke oven showing the construction of the parallel apertures 40 and channels therein through which the volatile matter from the coal passes from the oven to the place of condensation.

In these drawings 2 represents the fire-brick lined dome structure of the walls and 45 roof, 3 being the closable aperture in the crown through which the oven is charged with coal, 4 the uptake flue aperture, and opposite the flue the side door opening 5, through which the coke charge of the oven 50 is withdrawn. The floor 6 of the oven is uniformly sloped at a slight angle toward the side door 5 to facilitate withdrawal of the charge and the particular construction of the floor is as follows.

From a position 7 a short distance from the wall of the oven the sub-floor 8, con-

structed of fire-brick, drops vertically for about eighteen inches and therefrom slopes conically to a central well aperture 9 which is covered with a grating 10 and from which a branch pipe 12 closable with a stop-cock 12^x leads to the condensers in which the by-products are recovered.

The conical space within the sub-floor 8 is filled and packed with heavy gravel or rock of a size about two inches, and on the upper surface of this gravel fire-brick tiles 15 are laid in parallel rows toward the side of the oven in which is the side door 5 with an interspace of about three inches between each 70 row of tiles. These tiles 15 are bedded on fire-clay on the surface of the heavy gravel to insure a uniformly plane surface, the plane being sloped toward the side door at the grade of the floor level 6. Along the side 75 edges of these tiles 15 fire-bricks 16 are bedded and jointed with fire-clay, the upper sides of the bricks being checked, as at 17, for a reason which will be explained later, and along the middle of each row of tiles 15 80 between the rows 16, fire-bricks 18 are bedded and jointed, which bricks are without checks on their upper sides. The space between the adjacent bricks 16, that is, between each row of tiles is filled with coarse gravel 85 to the level of the checks 17.

Resting on the upper sides of the bricks 16 are fire-bricks 20, the width of the bricks 20 being such that they extend slightly beyond or overlap the outsides of the bricks 90 16 that are located beneath the bricks 20 and resting on each middle row of bricks 18 is a row of bricks 21, the middle of each side of which for a depth of about two inches is checkered as at 22 to form interspaces between them and the bricks 20, and therebeneath the sides of these bricks are beveled inward as at 23 to near where they seat upon the bricks 18.

These bricks 20 and 21 form the floor of 100 the coke oven which is therefore provided with parallel interspaces 22 through which the volatile matter from the coal being coked may freely pass into the trap channels 19 between the rows of bricks 16 and 18 and 105 therefrom through the checks 17 into the gravel filled interspaces and through the gravel filled conical space of the sub-floor 8 to the central well 9, to be conducted through the pipe 12 to the condensers.

The trap channels 19 of each row of tiles are toward the front of the oven connected

together as at 25 and each connected pair is provided with a separate closable cover plate 26 through which any accumulation of dust, etc., trapped in the channels may be periodically withdrawn.

5 In the roof of the oven above the uptake flue 4 a steam injector 27 is inserted and is obliquely directed downward, that its jet may not directly impinge on the surface of the charge.

10 In use, the oven is charged through the central aperture 3 to a depth of about three feet or to the approximate level of the upper side of the side door opening 5 which doorway is closed, preferably by bricking it up. The charge being kindled on the top adjacent the side door 5, the draft is first taken through the uptake flue 4 and the fire is allowed to spread over the whole upper surface of the charge until it attains a red flow. Thereafter the uptake flue is closed and a draft is induced, in any well-known way, through the gas delivery pipe 12, and this down draft is assisted by a stream of air 15 and steam at the injector 27.

20 The heat from the upper strata of the charge is thus drawn downward through it; the uniform distribution of the interspacing apertures 22 of the floor 6 and the conical form of the sub-floor 8 insuring the uniform distribution of the down draft through the whole surface of the charge. The volatile matter from the coal, released by the heat, passes as before described into the trap 25 channels 19 and therefrom through the checks 17 and through the gravel in the conical space between the floor 6 and the sub-floor 8, and is delivered through the pipe 12 to the necessary condensers, washers 30 and scrubbers, and the residual carbureted hydrogen gas may be utilized for the generation of steam in any convenient manner for the operation of the coking plant.

35 With this construction of oven the quality and quantity of the coke produced is improved and all available condensable residues are recovered as by-products.

40 As in all coking ovens, much of the success with this one depends on the supervision and attention to details in the regulation of the draft whereby the volatile elements are expeditiously removed with a minimum of combustion. These details, however, can form no part of the patent application, but the essential features of the invention lie in the conical form of the sub-floor 8, in the manner of supporting the oven floor 6 thereupon, in the uniformly distributed apertures of the main floor 6 45 and in the manner of trapping these apertures to avoid accumulation of dust and dirt obstructing the free passage and the provision for conveniently cleaning out the trap channels.

50 I do not desire to be confined to the par-

ticular form of fire-bricks used in the construction of the floor and its trap channels, as set forth in the foregoing description and illustrated in Fig. 4 of the drawings, although I believe that to be the simplest 70 and cheapest manner of attaining the desired result, nor to the application of the same solely to the bee-hive form of oven.

75 The essential features of the invention, which are believed to be novel and on which the protection of Letters Patent is desired, are fully set forth in the following claims.

Claims:

1. A coke oven having a charging aperture in the crown, an uptake flue and a doorway through which the charge of coke may be withdrawn, said oven having a floor of fire-brick with uniformly distributed interspaces between the bricks, a space beneath the floor, a permeable filling in said space 80 forming support for the fire-bricks, and means for connecting said space beneath the floor bricks to a pipe delivering to the condensers.

90 2. A coke oven of the class described having a sub-floor which is depressed toward a central aperture delivering to the condensers, a grating over the central aperture, a permeable filling within the depression, a floor of fire-brick supported on the permeable filling, said floor having interspaces between the bricks through which the volatile constituents of the coal given off during coking may be induced to flow and pass through the permeable filling to the condensers.

95 3. A coke oven of the class described having a sub-floor which is depressed toward a central aperture delivering to the condensers, a grating over the central aperture, a permeable filling within the depression, a floor 100 of fire-brick supported on the permeable filling, the bricks of said floor being arranged in parallel rows toward the front of the oven and provided with interspaces between the bricks of each row, said floor having also 105 trap channels beneath each row of interspaces, which channels are produced toward the front of the oven and are closable at the front end with cover plates, the walls of said channels being provided with passages 110 in their upper part through which the volatile elements given off by the coal during coking may be induced to pass from the channels through the permeable filling to the condensers.

115 4. A coke oven of the class described having a sub-floor which is sloped from adjacent the walls to a central aperture delivering to the condensers, a grating over the central aperture, a permeable filling within the 120 sloped depression of the sub-floor, fire-brick tiles resting on the permeable filling and arranged in parallel rows directed toward the front of the oven with an interspace between each row, each row of said tiles having two 125

parallel channels which are connected to ducts which pass through the front of the oven and are closable at the front end with cover plates, the outer wall of each channel being provided with passages connecting it with the interspace between the rows of tiles, and a floor of fire-brick arranged in rows and supported on the walls of the channels with interspaces between the rows immediately 5 over the channels whereby the volatile constituents of the coal given off during coking may be induced to flow through the interspaces of the main floor into the channels and therefrom into the interspaces between 10 the rows of floor-supporting tiles and through the permeable filling to the central delivery outlet to the condensers.

5. In a coke oven of the class described having a sub-floor that is depressed from adjacent the walls of the oven to a central aperture delivering to the condensers, a grating over the central aperture, a permeable filling within the depression adapted to support the main floor of the oven, rows of fire-brick 20 tiles supported on the permeable filling of

the depression in parallel rows toward the front of the oven with an interspace between each row, a row of fire-bricks along the edges of each row of tiles and a row of fire-brick along the middle of each row of tiles forming two channels along each row, which channels join together and are produced as a duct through the front of the oven and are closable at the front end with cover plates, the fire-bricks along the edges of each row of 30 tiles being checked across the upper surface to connect the channels to the interspaces between their supporting tiles, and a floor of fire-brick arranged in rows to correspond with those of the supporting bricks and having interspaces between the rows over the channels whereby the volatile constituents of the coal given off during coking may pass through the interspaces of the floor into the channels and therefrom through the permeable filling to the central aperture delivering 35 to the condensers.

In testimony whereof I affix my signature.

MATTHEW MARSHALL, SENR.
